UNITED STATES PATENT OFFICE.

ERNEST LEGG AND GEORGE H. WRIGHT, OF GRANVILLE, OHIO.

CEMENT RAILROAD-TIE.

No. 851,601.

Specification of Letters Patent.

Patented April 23, 1907.

Application filed November 15, 1906. Serial No. 343,644.

To all whom it may concern:

Be it known that we, ERNEST LEGG and GEORGE H. WRIGHT, citizens of the United States, residing at Granville, in the county of Licking and State of Ohio, have invented certain new and useful Improvements in Cement Railroad-Ties; and we do declare the following to be a full, clear, and exact description of the invention, such as will enable others skilled in the art to which it appertains to make and use the same.

This invention relates to concrete railway ties.

The object of the invention is to improve the manner of construction of the tie whereby it shall possess great strength, and be prevented, when in use, from cracking from the jars or vibrations incident to the passage of trains over the tracks.

20 A further object is to improve the manner of locking or assembling the rails with the tie whereby the danger of the rails working loose or spreading is positively precluded.

25 A further object is to provide a novel means to cushion the rails at their point of connection with the ties.

With the above and other objects in view, as will appear as the nature of the invention is better understood, the same consists in the 30 novel construction and combination of parts of a concrete railway tie as will be hereinafter more fully described and claimed.

In the accompanying drawings forming a part of this specification, and in which like characters of reference indicate corresponding parts: Figure 1 is a view in perspective, partly broken away, exhibiting the railway tie of the present invention, and the manner of locking or securing the rails thereto; Fig. 2 is a similar view of a reinforcing plate used in connection with the tie; Fig. 3 is a perspective detail view of the tie; Fig. 4 is a perspective view of a cushioning element used in connection with the tie; and Figs. 5 and 6 are detail views of a wedge and a key used in clamping or locking the rails in position.

Referring to the drawings, 1 designates the tie which is constructed of cement and as usual is rectangular in shape. Included in the tie at the time of its being molded is a reinforcing plate 2, which may be made either of cast or stamped metal and is provided, adjacent to its terminal, with a brace 55 wedge 3 and 4 respectively, the outer faces of

which are rounded or curved to give the greatest strength and the inner faces of which are flat and disposed approximately at right angles to the length of the plate. The plate has on its upper surface, and near each of the braces, pairs of sockets 5 and 6, that are arranged in staggered order, with the orifices therein opening in opposite directions, the distance between the outer walls of each pair of sockets being substantially equivalent to the width of the rail base. These sockets are adapted to be engaged by keys 7, each having at its lower end a toe 8 to engage a socket and at its upper end a head 9 to overlap the base of the rail.

70 The reinforcing plate is herein shown as relatively broad at its center portion and tapered toward each end, but this is not essential as it may be of the same width throughout and still be within the scope of the invention.

Adjacent to each terminal of the tie is formed a double depression constituting a cushion seat, the lower depression 10 being engaged by a lug or projection 11 on the under side of the cushion 12, which is made preferably of wood, and the upper depression 13, which extends throughout the width of the tie, being engaged by the base portion or rail engaging portion 13 of the cushion. The 85 object of this cushion is to reduce the strain on the rail at the point where it bears on the tie and at the same time to render the connection between the rail and the tie of a yielding character.

90 When a rail is placed upon the tie, the two keys 7 are positioned as shown in Fig. 1, and wedges 14 are then driven in between the back of one key and the brace 3 or 4, as the case may be, and between the other key and the wall of the key-opening in the tie, thereby tightly forcing the keys against the base of the rail and the rail against the cushion and at the same time positively locking the rail against possibility of working loose or becoming detached.

105 It will be seen from the foregoing description that while the improvements herein defined are simple in character, they will be thoroughly efficient for the purposes designed and will result in a large saving to railway companies inasmuch as the only portions that will deteriorate with age are the cushions which may readily be replaced when no longer serviceable.

Having thus described my invention, what I claim as new, is:—

1. The combination with a concrete tie, of a reinforcing plate provided with terminal wedge braces, and intermediate oppositely disposed key sockets.
2. The combination with a concrete tie, of a reinforcing plate embedded therein and provided with terminal wedge braces and intermediate oppositely disposed key sockets.
3. The combination with a concrete tie and a reinforcing plate embedded therein and provided with terminal wedge braces and intermediate oppositely disposed sockets, of keys having toes to engage the sockets and heads to engage a rail base, and wedges to engage with the keys and with the wedge braces.
4. The combination with a concrete tie provided in its upper face adjacent to its terminals with transversely-disposed seats having intermediate depressions, of rail cushion-

ing elements engaging the seats and having intermediate projections to engage the depressions.

5. The combination with a concrete tie, of a reinforcing plate provided with terminal wedge braces and intermediate oppositely-disposed sockets, all parts of the plate being wholly inclosed by the tie.

6. As a new article of manufacture, a reinforcing element for concrete railway ties, comprising a plate having terminal upstanding wedge braces and pairs of oppositely-disposed key sockets disposed adjacent thereto.

In testimony whereof we have hereunto set our hands in presence of two subscribing witnesses.

ERNEST LEGG.
GEORGE H. WRIGHT
